US0D1063656S

(12) **United States Design Patent** (10) Patent No.: **US D1,063,656 S**
Li et al. (45) Date of Patent: ** Feb. 25, 2025

(54) **PROBE HOLDER FOR A TEMPERATURE MEASURING DEVICE**

(71) Applicant: **Shenzhen Typhur Technology Co., Ltd.**, Shenzhen (CN)

(72) Inventors: **Chengmin Li**, Guangdong (CN); **Shuhong Wang**, Guangdong (CN)

(73) Assignee: **Shenzhen Typhur Technology Co., Ltd.**, Shenzhen (CN)

(**) Term: **15 Years**

(21) Appl. No.: **35/519,022**

(22) Filed: **Jul. 26, 2023**

(80) **Hague Agreement Data**

Int. Filing Date: **Jul. 26, 2023**

Int. Reg. No.: **DM/232906**

Int. Reg. Date: **Jul. 26, 2023**

Int. Reg. Pub. Date: **Nov. 17, 2023**

(30) **Foreign Application Priority Data**

May 23, 2023 (CN) 202330307686.9

(57) **CLAIM**

The ornamental design for a probe holder for a temperature measuring device, as shown and described.

DESCRIPTION

1. Probe holder for a temperature measuring device

1.1 : Perspective

1.2 : Perspective

1.3 : Front

1.4 : Back

1.5 : Left

1.6 : Right

1.7 : Top

1.8 : Bottom

1.9 : Unfolded

The broken lines in the drawings illustrate portions of the probe holder for a temperature measuring device that form no part of the claimed design.

1 Claim, 9 Drawing Sheets
